UNITED STATES PATENT OFFICE.

JOSEPH H. JOLLEY, OF PHILADELPHIA, PENNSYLVANIA.

DESIGN FOR A STAIR-BUTTON.

SPECIFICATION forming part of Design No. 19,754, dated April 8, 1890.

Application filed March 3, 1890. Serial No. 342,473. Term of patent 7 years.

To all whom it may concern:

Be it known that I, JOSEPH H. JOLLEY, a citizen of the United States, residing at Philadelphia, in the county of Philadelphia and State of Pennsylvania, have invented and produced a new and original Design for a Stair-Button, of which the following is a specification, reference being had to the accompanying drawings, forming part hereof.

Figure 1 is a front view of a stair-button showing my design. Fig. 2 is a side elevation of the same.

The stair-button according to my design

represents the form of a lion's head A, provided with a faceted pyramidal ornament a 15 between the jaws.

I claim—

The design for a stair-button, substantially as shown and described.

In testimony whereof I have hereunto signed 20 my name this 17th day of October, A. D. 1889.

JOSEPH H. JOLLEY.

In presence of—

JOHN JOLLEY, Jr.,
CHAS. BUSH.
